UNITED STATES PATENT OFFICE.

MOSES RHEINSTROM, OF CINCINNATI, OHIO.

CLOSING DEVICE FOR BOTTLES, &c.

SPECIFICATION forming part of Letters Patent No. 447,974, dated March 10, 1891.

Application filed November 25, 1890. Serial No. 372,631. (No model.)

To all whom it may concern:

Be it known that I, MOSES RHEINSTROM, a citizen of the United States, residing at Cincinnati, in the county of Hamilton and State 5 of Ohio, have invented certain new and useful Improvements in Closing Devices for Bottles and other Vessels; and I do hereby declare the following to be a full, clear, and exact description of the invention, such as will 10 enable others skilled in the art to which it appertains to make and use the same.

My invention relates to means for sealing or closing bottles and other vessels after a portion of the contents thereof have been with- 15 drawn; and it consists, essentially, in devices whereby a flexible sack is inflated to required dimensions within a receptacle.

My invention is hereinafter fully described, illustrated in the drawings, and specifically 20 pointed out in the claims.

Referring to the accompanying drawings, wherein like letters of reference point out similar parts on each figure, Figure 1 represents an ordinary wine-bottle closed with a 25 cork through which is inserted a tube carrying attachments embodying my invention. Fig. 2 is a similar view showing the tube elevated and the flexible sack distended, the detachable ball employed for inflating purposes being ad- 30 justed upon the valve-cup. Fig. 3 is a like view, the inflating-ball removed and the valve-closing plug being inserted in place. Fig. 4 is a detail sectional view of a portion 35 of the inflating-ball, showing its interior construction. Fig. 5 is a detail view of the cup attached to the upper end of the tube, parts being broken away, showing interior construction. Fig. 6 is a view of the lower end 40 of the air-duct tube, showing the eduction-opening, the expandible sack being removed.

In the drawings, A is an ordinary bottle; B, a cork, preferably made of rubber, having a bore b, through which the air-duct tube C is free to pass vertically, said tube also having an eduction-orifice c and an inflow-opening c', for a purpose that will presently be set forth.

D is an expandible sack, preferably of thin rubber, into which the lower end of the tube 50 C is inserted, said sack at its upper end being closely connected by means of wrapped wire or any suitable means to the tube, which

is preferably provided with an extending head or flange c², over which the mouth of the sack is passed, the object being to have a 55 hermetical closure at the point of connection.

Adjusted at the top of the tube C is a valve-cup D', provided with an interior yielding diaphragm d, onto which rests the lower end of a propellible stud or pin d', so that a vertical downward pressure of said plug will 60 distend said diaphragm and allow air to flow downward through one or more peripheral orifices d² into the tube C and be therefrom expelled to distend the sack. I do not limit 65 myself to this special construction; but any suitable valve will be within the scope and purview of my invention.

E is a removable rubber ball having a lower open nipple e, that will closely fit into 70 the upper end of the cup-valve, and when so adjusted will force downward the stud d', thereby actuating the diaphragm and opening a conduit for admission of air to the tube and therefrom to and within the sack. It will 75 be readily understood that by repeated compression of the ball E said sack will be supplied with air and be distended, as illustrated in Fig. 2.

As before described the duct-tube is mov- 80 able vertically through the aperture of the cork, whereby the sack can be elevated to any desired point within the bottle. After the sack is inflated to a required degree and at a predetermined elevation the ball E is discon- 85 nected from the cup and a supplementary cork c³ is placed as a closure within the upper opening of the cup, whereby the stud is protected and the admission or escape of air is prevented. When, however, it is desired 90 to withdraw the air from within the inflated sack, the cork c³ is removed and the valve-pin d' pressed downwardly, thus opening the valve of the cup, causing the air to escape 95 upwardly and admitting the removal of the tube and its attached sack through the neck of the bottle.

In practice my invention is intended to close that portion of the interior of a vessel from which the contents have been partially 100 removed.

In the drawings I have illustrated an ordinary bottle, but do not desire to be understood as limiting myself to such inclosures.

It is adapted for use upon receptacles of any shape or conformation.

It principally relates to inclosures that contain wine, beer, effervescent or gaseous liquids, which from time to time are only partially withdrawn from the vessel, and the quantity thereof remaining thereby becoming liable to be soured or otherwise deteriorated.

10 The object of my invention is to keep the remaining liquid contents of a receptacle from which a portion has been withdrawn protected from contact with the air that naturally fills up the vacancy occasioned by 15 reason of withdrawal of portions of the liquid contents from time to time. The quantity left, if wine, is liable to become sour; if gaseous liquid, to become flat; and other descriptions of liquid will in various ways deteriorate by reason of contact with the atmosphere between its upper surface and the tubular neck or other outflow member of the vessel, this defect being present even when the ordinary stopper is inserted in place, and 20 especially if there be any imperfect corkage.

It is manifest that while my invention is specially adapted for closing the vacancy occurring when simple liquids are withdrawn from bottles or other vessels, it is also applicable for use for semi-liquids or solids of an effervescent or volatile or deliquescent nature—such, for instance, as preserves, jams, medicinal compounds—necessary to protect from atmospheric influence.

35 Having thus described my invention, what I claim, and desire to secure by Letters Patent of the United States, is—

1. In the herein-described device for sealing portions of the interior of a vessel from 40 which the contents have been partially withdrawn, the combination of an air-duct tube

and an attached distensible sack with a cork having a vertical bore, through which the tube will be free to move vertically to desired elevations, and means, as set forth, for 45 expanding said sack by introduction of air therein through said duct, said duct being provided at its upper end with a valve controlling the admission and expulsion of air through the induction-opening of said tube, 50 as and for the purpose intended, substantially as described.

2. The herein-described device for sealing portions of a vessel the contents of which have been partially withdrawn, which consists 55 in an air-duct tube provided with an ingress and egress orifice, said tube carrying at its lower end an expansible sack and at its upper end a cup supplied with a valve controlling the admission and expulsion of air to and 60 from the expansible sack, said cup provided with an independent removable cork c^3 , all in combination with a closing-cork B, having a vertical bore b , which receives the duct-tube, substantially as described. 65

3. The herein-described device for sealing portions of a vessel the contents of which have been partially withdrawn, consisting of an orificed cork B, carrying an air-duct C, having attached to its lower end an expansible sack D and to its upper end a valve-cup D', provided with supplementary cork c^3 , all in combination with removable compress-ball E, having apertured nipple e, as and for the purpose intended, substantially as described. 70 75

In testimony that I claim the invention above set forth I affix my signature in presence of two witnesses.

MOSES RHEINSTROM.
